UNITED STATES PATENT OFFICE

THOMAS DUNBAR AND ETHAN I. DODDS, OF PULLMAN, ILLINOIS,
ASSIGNORS TO THE PULLMAN COMPANY, OF CHICAGO, ILLINOIS,
A CORPORATION OF ILLINOIS.

SIDE OR CENTER SILL FOR CARS.

No. 825,043.

Specification of Letters Patent.

Patented July 3, 1906.

Application filed October 30, 1905. Serial No. 285,158.

To all whom it may concern:

Be it known that we, THOMAS DUNBAR and ETHAN I. Dodds, citizens of the United States, residing at Pullman, in the county of Cook and State of Illinois, have invented certain new and useful Improvements in Side or Center Sills for Cars, of which the following is a specification.

In order to produce a bellied metallic side or center sill for railway-cars possessing both light weight and strength, the former being secured without sacrificing the latter, we have invented a sill preferred mechanical embodiments of which are described herein after and illustrated in the accompanying drawings. It involves two end beams joined together by upper and lower bars which are spaced apart and held in position by a number of short oppositely-inclined strips or lattice-work attached thereto. The lower bar desirably extends substantially the entire length of the structure, while the upper bar merely connects the inner portions of the end beams, the complete construction possessing great rigidity and facilities for repairs, since the sill is made of a number of small parts. Our invention, however, is not limited to a lower bar extending the full length of the sill, a short bar attached to the ends of the end beams falling within the scope of our invention.

In the accompanying drawings, which form a part of this specification, Figure 1 is a side elevation of substantially one-half of a sill embodying our invention. Fig. 2 is a vertical cross-section on line 22 of Fig. 1 as viewed in the direction indicated by the arrow. Fig. 3 is a side elevation of a portion of a modified from of sill. Fig. 4 is a horizontal section looking downwardly on line 44 of Fig. 3, and Fig. 5 is a vertical cross-section on line 55 of Fig. 3.

The sill illustrated in Figs. 1 and 2 includes two end beams 10, of which only one is shown, each having an integral inwardly-extended top flange 11 and being deeper at its inner than at its outer end 10^a and 10^b, respectively. To the outer surface of each end 10^a is riveted a splice-plate 12, to the upper protruding part of which is fastened, by means of rivets, an end of a connecting channel-bar 13 with inwardly-turned top and bottom flanges 14 and 15. At the lower portion of the sill

we employ an angle-bar 16, which extends substantially the full length of the sill, being riveted to the end beams 10 and to the splice-plates 12. Lattice-work 17, which includes a plurality of inclined strips riveted together and to the parts which they connect, is attached to bars 13 and 16, holding the same spaced apart and in proper position. It will be noted that by this construction we secure a metal sill of great strength and rigidity, but which nevertheless is of comparatively light weight, owing to the use of the lattice-work between the top and bottom connecting-bars.

In Figs. 3, 4, and 5 there is illustrated a modified form of sill which includes two end beams 20, of which only one is shown, each having inwardly-turned top and bottom flanges 21 and 22, respectively, the inner end of each beam being deeper than its outer end. An upright stake 23, T-shaped in cross-section, is disposed vertically against the outer surface of the inner end portion of each beam 20. Channel-bars 24 and 25, which are spaced apart vertically one above the other, overlap the inner ends of beams 20 and are riveted thereto and to the flanges of the side stakes. In order to permit the top surface of bar 24 to be in the same plane with those of beams 20, the flanges of the latter are cut away, as at 26, to allow for the overlapping ends of bar 24. Flange 22 may be slightly cut away to provide for the ends of bottom bar 25, if desired. In this construction the top bar 24 acts under compression and the bottom bar under tension, the two being spaced apart and tied together by means of lattice-work 27, which comprises oppositely-inclined strips riveted to the bars and to each other, as shown in Fig. 3.

It will be apparent to those skilled in the art that we have produced a construction which because of its light weight and considerable strength allows us to build a car of the usual capacity with sills under ordinary weight.

Our invention is not limited to the details of construction shown and described, and for that reason should not be restricted there-to except to the extent that the details are made the subject-matter of specific claims.

We claim—

1. A sill for a railway-car having two end beams, and top and bottom bars joining the

- inner ends of said beams, substantially as described.
2. A sill for a railway-car having two end beams, top and bottom bars spaced apart 5 joining the inner ends of said beams, and lattice-work connecting said bars, substantially as described.
3. A sill for a railway-car having two end beams deeper at their inner ends than at their 10 outer ends, top and bottom bars spaced apart joining the inner ends of said beams, and lattice-work connecting said bars, substantially as described.
4. A sill for a railway-car having two end 15 beams deeper at their inner ends than at their outer ends and each having a top flange, a top channel-bar and a bottom angle-bar spaced apart and joining the inner ends of said beams, and lattice-work connecting said bars, substantially as described.
5. A sill for a railway-car having two end 20 beams, a splice-plate secured to the inner end of each beam, a top bar secured to and connecting said splice-plates, and a bottom bar extending substantially the full length of the 25 sill and riveted to the end beams and to said splice-plates, substantially as described.
6. A sill for a railway-car having two end beams, and a splice-plate secured to the inner 30 end of each beam, a top bar secured to and connecting the upper portions of said splice-plates, a bottom bar spaced from said top bar extending substantially the full length of the 35 sill and riveted to the end beams and splice-plates, and lattice-work connecting said top and bottom bars, substantially as described.
7. A sill for a railway-car having two end beams deeper at their inner than at their 40 outer ends, each having an integral inwardly-turned flange, splice-plates secured to the outer surfaces of the inner ends of said beams, a channel-bar secured to and connecting the upper portions of said splice-plates, a bottom angle-bar extending substantially the full 45 length of the sill and riveted to said end
- beams and to said splice-plates, and lattice-work connecting said channel and angle bars, substantially as described.
8. A sill for a railway-car having end beams, and vertically-spaced bars overlapping 50 the inner ends of said beams and secured thereto, substantially as described.
9. A sill for a railway-car having end beams, a plurality of bars spaced apart and overlapping the inner ends of said beams and 55 secured thereto, and lattice-work connecting said bars, substantially as described.
10. A sill for a railway-car having end beams, spaced bars overlapping the inner 60 ends of said beams, side stakes, and rivets securing together said end beams, side stakes, and spaced bars, substantially as described.
11. A sill for a railway-car having end beams, spaced bars overlapping the inner 65 ends of said beams, side stakes, and rivets securing together said end beams, side stakes, and spaced bars, and lattice-work connecting together said spaced bars, substantially as described.
12. A sill for a railway-car having two end 70 channel-beams deeper at their inner ends than at their outer ends, spaced channel-bars overlapping the inner ends of said end beams and disposed against the inner surfaces of their webs, vertical side stakes disposed 75 against the outer surfaces of said webs opposite the overlapping ends of said spaced channel-bars, rivets securing together said end beams, side stakes, and spaced channel-bars, and lattice-work connecting together said 80 spaced channel-bars, substantially as described.
- As evidence that we claim the foregoing as our invention we have hereunto subscribed our names in the presence of two witnesses. 85
